(57) **CLAIM**

The ornamental design for a nozzle for water purifier as shown and described.

DESCRIPTION

1. Nozzle for water purifier

1.1 : Perspective

1.2 : Front

1.3 : Back

1.4 : Left

1.5 : Top

1.6 : Bottom

1.7 : Cross sectional

1.8 : Reference

The omitted right view is a mirror image of the left view; reproduction 1.7 is a vertical cross-sectional view of reproduction 1.5; reproduction 1.8 shows a state in use of the claimed design wherein broken lines depict environmental structure and form no part of the claimed design.

1 Claim, 8 Drawing Sheets
